UNITED STATES PATENT OFFICE.

GUSTAV A. HARTER, OF CHICAGO, ILLINOIS.

ELECTRIC FIXTURE.

1,250,581.

Specification of Letters Patent. Patented Dec. 18, 1917.

Application filed June 22, 1914. Serial No. 846,419.

To all whom it may concern:

Be it known that I, GUSTAV A. HARTER, a citizen of the United States, residing at Chicago, in the county of Cook and State 6 of Illinois, have invented certain new and useful Improvements in Electric Fixtures, of which the following is a specification.

This invention relates to fixtures for electric lamps, and more particularly to a fixture in which a socket, globe and shade are freely adjustable to facilitate the installation thereof and to accommodate lamps of different sizes so that the maximum efficiency for lamps of different sizes may be 15 obtained with the same fixture by varying the position of the several adjustable parts.

For the attainment of these ends and the accomplishment of other new and useful objects, as will appear, this invention consists 20 in the features of novelty in the construction, combination and arrangement of the several parts generally shown in the accompanying drawing and described in the specification, but more particularly pointed out 25 in the appended claims.

In the drawing, Figure 1 is a view of a fixture constructed in accordance with the principles of my invention; Fig. 2 is a sectional view on the line 2—2 of Fig. 1; Fig. 30 3 is a sectional view on the line 3—3 of Fig. 1; Fig. 4 is a view of a split supporting ring, and Fig. 5 is a detail view of a lamp gripping device.

To provide a fixture which is adapted to 35 accommodate different sized electric lamps, particularly the new high power nitrogen lamps, it is necessary that some adjustability be provided whereby the maximum efficiency of the lamp is obtained. For instance, with 40 a small lamp the lighting filament is at a different elevation than a larger lamp. This necessitates either the raising of the globe, the shade or the socket, and the best way to provide for such adjustability is to make 45 both the globe holder and the socket adjustable with respect to the shade.

In this invention a threaded member 7 is attached to a conduit or fixture pipe 8 to 50 provide a support. A yoke member 9 has sides 10 (see Fig. 3) turned downwardly to engage a nut 11 which is threaded on the lower end of the member 7, the yoke 9 forming a support for removable arms 12 which depend therefrom.

A lamp socket 13 is formed with lateral 55 grooves 14 into which the arms 12 extend, and the arms are provided with screws 15 which extend through them and engage notches 16 in the bottoms of the grooves 14 of the socket. These arms 12 are attached 60 to the yoke 9 by means of screws 17 so that longer or shorter arms may be substituted, and the socket 13 is adjustable up and down with respect to the arms to any predetermined number of different positions for each 65 arm. In order to prevent the arms from swinging outwardly, and in order to hold the screws in position in the arms a sleeve or band 18 is provided slidable up and down about the socket and upon the arms so that 70 the heads of the screws 17 are engaged and prevented from outward movement, and the arms are bound in place and prevented from swinging outwardly.

Disposed above the yoke 9 and surrounding the threaded member 7 is a shade or globe supporting shell 19, the depending end of which is formed with a flare 20 upon which a supporting ring 21 or a number of such rings are disposed. These rings are 80 removable and for this purpose may be split and hinged together, as shown in Fig. 4, or may be simply made in sections and placed in position. These rings extend outwardly beyond the flaring extremity of the 85 shell 19 and are adapted to engage a shoulder of a shade or globe support 22, the inside diameter of which is sufficient to allow the support to pass freely over the flared end of the shell 19 when the split ring 21 is 90 removed. In order to remove the ring or to place it in position the support 22 is moved outwardly to the dotted position shown in Fig. 1, whereupon one or more of the rings 21 may be placed in position, depending 95 upon the desired position of the globe or shade supported thereby. Outside of the support 22 is a guard 23 which is movable upwardly independent of the support 22 but is also provided with a shoulder which engages the shoulder of the support 22 so that the guard 23 is moved upwardly with it. If desired the guard and the support may be secured together by means of a fastening device 24, and a shade, globe or reflector 25 100 is held by the support 22 and is bound in position by means of the guard 23.

Above the shell 19 and surrounding the

threaded member 7 is a shade supporting plate 26 formed about its periphery with an offset groove in which is seated a split ring 27 which extends beyond the edges of the plate 26. Supported by the split ring 27 is a shade 28 which has a perforation 29 slightly larger than the supporting plate 26 so that the supporting plate passes freely through the opening 29 when the split ring 5 is removed. The split ring may be easily removed by separating the plate 27 and the shade slightly and moving the split ring by means of the split portion thereof on either side of the shade itself or on either 10 side of the plate 26, the normal position of the split ring being between the plate and the shade. On top of the shade and surrounding the threaded member 7 is a shade guard 30 which protects the shade from the 15 weather preventing any water from settling at the top of the shade and also holding the shade holder firmly in position. A lock-nut 31 is threaded on the member 7 above the guard 30 and binds the guard, the plate 20 26, the shell 19 and the yoke 9 all firmly together.

With this construction it is obvious that the shade 28 may be raised or lowered without effecting the position of the socket 13 30 or the globe 25; the socket may be adjusted independently by simply varying the position of the socket in the arms 12; the position of the socket may also be varied by substituting longer or shorter arms; and the 35 shade or globe 25 may be raised or lowered by inserting or removing split rings. Thus a single fixture may be used to accommodate large or small lamps and the several parts are relatively adjustable so that the 40 maximum efficiency will be obtained from the lamp by reason of the position of the lamp with respect to the globe and to the shade.

In order to prevent a lamp from becoming easily disengaged from the socket, a metal strip 32, preferably of phosphor bronze or some other resilient conducting material, is secured to the inner end of a shell 33 of the socket extending outwardly 50 therefrom and so disposed that the threaded end of a lamp inserted in the shell will compress the strip into the grooves of the shell and will thus cause the lamp socket to closely engage the lamp for holding it firmly 55 but yieldingly in position.

What I claim is:

1. In an electric fixture, a support, arms secured to the support, a lamp socket adjustable in height with respect to the arms, 60 and a band extending about the socket adapted to engage the lower free extremities of the arms to hold them inwardly in position to be engaged by the socket.

2. In an electric fixture, the combination 65 with a support, of arms adapted to be re-

movably secured to the support and extending parallel with each other, a socket with grooves and notches adjustable with respect to the arms, means to secure the socket adjustably to the arms, and a movable binder 70 adapted to engage the fastening means and to press the arms inwardly and to hold the socket in any adjusted position.

3. In an electric fixture, the combination with a support, of a lamp globe holder vertically adjustable with respect to the support, 75 a vertically adjustable socket comprising a socket member with opposite vertical grooves having spaced notches therein, arms each adjustably secured to the support at one of the ends adapted to be disposed in a groove of the socket, means in connection with the free ends of the arms to engage the notches of the socket to hold the socket in position, and binding means movable to hold the engaging means in contact with the notches of the socket and to prevent the arms from spreading whereby the socket is held in any desired adjustable position.

4. In an electric fixture, the combination with a support, of a shell flared outwardly at the bottom, a unitary split ring supported by the outwardly flared portion, and a globe supporter shaped to engage the split ring when it is in position on the flared end of 95 the shell and freely movable over the flared end of the shell when the split ring is removed.

5. In an electric fixture, the combination with a shell flared at the lower end, of means 100 engaged by the flared end of the shell and extending outwardly beyond the said flared end, comprising connected sections applied thereto as a unit, and a movable shade or globe support adapted to be engaged by the 105 said means but freely movable over the flared end of the shell when the means is removed.

6. In an electric fixture, the combination with a supporting shell with an outward 110 projection at the bottom, of a removable hinged split ring adapted to be engaged by the projection and extending beyond the outer edge of the projection, and a globe or shade support having a shoulder adapted to 115 be engaged by the split ring movable upwardly therefrom so that the split ring may be inserted or removed and freely movable over the projection of the supporting shell when the split ring is removed.

7. In an electric fixture, the combination with a support, of a lamp socket vertically adjustable with respect to the support, a supporting shell secured to the support having a flared lower extremity, a removable 125 split ring adapted to be engaged by the flared end of the shell and extending outwardly beyond the flared end, a plurality of them adapted to be disposed one above the other about the shell, and a shade or globe 130

support vertically adjustable with respect to the shell adapted to be engaged by the uppermost removable ring and freely movable over the flared end of the shell when all of the rings are removed.

8. In an electric fixture, a supporting shell flared outwardly at the bottom, a removable ring supported by the flared end and extending beyond it, a globe or shade support having a shoulder adapted to be engaged by the removable ring and freely movable over the flared end when the ring is removed, and a globe or shade guard disposed on the outside of the globe or shade support freely movable upwardly with respect to the support and movable bodily upward with the support, the guard fitting the support closely to strengthen it.

9. In an electric fixture, the combination with a support, of a shade having a perforation larger than the support, a shade supporting plate smaller in size than the perforation, and a unitary split ring adapted to engage the edges both of the perforation of the shade and of the shade supporting plate whereby the shade may be raised or lowered above or below the shade supporting plate by removing the split ring.

10. In an electric fixture, the combination with a support, of a shade supporting plate, a shade having a perforation through which the plate passes freely, and a one-piece split ring to engage the outer edges of the plate and the inside edges of the perforation of the shade.

11. In an electric fixture, the combination with a support, of a lamp socket vertically adjustable with respect to the support, a globe support independently adjustable with respect to the socket and the said support, a shade support comprising a plate secured to the first named support, a split ring extending beyond the edges of the plate, and a shade with a perforation larger than the supporting plate and adapted to be engaged by the split ring.

12. In an electric fixture, the combination with a threaded member, of a yoke supported thereby, removable arms depending from and adjustably secured to the yoke, a lamp socket having a groove in which the arms extend having notches at spaced distances in the groove, adjusting screws movable through the arms to engage the notches, a clamping band movable over the ends of the screws to hold them in the notches and to prevent the arms from spreading, a shell disposed above the yoke member having a flared lower end, a split ring engaged by the flared end and extending outwardly beyond it, a shouldered globe support adapted to be engaged by the ring and freely movable over the projection of the shell, a shade supporting plate disposed above the support shell, a split ring supported by and

extending beyond the plate, a shade with a perforation larger than the plate supported by the outer edges of the split ring, a shade guard extending over the outside of the shade, and means to bind the yoke, the sleeve, the plate and the guard together upon the said threaded member.

13. In an electric fixture, a support and arms depending therefrom, a lamp socket, means extending inwardly from the arms to engage the socket, and means movable over the arms to hold them inwardly against the socket.

14. In an electric fixture, a support and arms depending therefrom, a lamp socket, means extending inwardly from the arms to engage the socket, and a ring movable downwardly over the arms to confine them and to hold said means in engagement with the socket.

15. In an electric fixture, the combination with a support flared outwardly, hinged removable means supported by the flared portion and extending outwardly beyond it, and a globe supporter adapted to engage the extending portion of the said member when it is in position on the flared end of the support and freely movable over the flared end when the said member is removed.

16. In an electric fixture, the combination with a support flared outwardly at the bottom, of a bodily removable sectional ring engaged by the flared portion and extending outwardly beyond it, and a globe or shade support having a shoulder adapted to be engaged by the ring vertically adjustable therefrom so that the ring may be inserted or removed, and shade support being freely movable over the flared portion when the ring is removed.

17. In an electric fixture, a supporting shell flared at the bottom, a removable shouldered and hinged sectional ring supported by the flared end and extending beyond it, and a globe or shade support having a shoulder adapted to be engaged by the shoulder of the ring and freely movable over the flared end when the ring is removed.

18. In an electric fixture, a supporting shell flared at the bottom, a shouldered removable ring having a reduced portion substantially the size of the flared end and a shoulder extending beyond it, and a globe or shade support having a portion to fit the reduced portion of the ring closely and a shoulder to engage the shoulder of the ring whereby the shade supporter is held firmly and prevented from wobbling or from a lateral movement.

19. In an electric fixture, the combination with a shade having a perforation and a support therefor comprising means larger in extent but insertable through the perforation for engaging the inside edge of the per-

foration of the shade, and clamping means engaging the outside edge of the perforation binding the shade in place.

20. In an electric fixture, the combination with a support, of a shade with a perforation through which the support passes freely, a member free from actual connection with the support or the shade adapted to be inserted through the perforation of the shade by a movement relative thereto and adapted to engage both the edge of the perforation and the support to uphold the shade, and clamping means attachable to the support extending over the shade for binding the shade in position.

21. In an electric fixture, the combination with a support having a threaded nipple, means in connection with the support for holding a lamp therein, a shade having a perforation through which the support freely passes, a member adapted to be inserted through the perforation of the shade and to be disposed between the shade and

the support engaging the outer edges of the support and the inner edges of the perforation for upholding the shade, and clamping means attachable to the nipple of the support for binding the shade and the said member in place on the support.

22. In an electric fixture, the combination with a shade having a perforation, and a support therefor comprising means larger in extent but insertable through the perforation for engaging the inside edge of the perforation of the shade, and clamping means for engaging the outside edge of the perforation binding the shade against the support and covering the perforation.

In testimony whereof I have signed my name to this specification, in the presence of two subscribing witnesses, on this 19th day of June, A. D. 1914.

GUSTAV A. HARTER.
